FUEL SUPPLY SYSTEM FOR INTERNAL-COMBUSTION ENGINES

Filed Sept. 11, 1946

UNITED STATES PATENT OFFICE

2,586,004

FUEL SUPPLY SYSTEM FOR INTERNAL-COMBUSTION ENGINES

Reginald Henry Douglas Chamberlin, London, England, assignor to D. Napier & Son Limited, London, England, a company of Great Britain

Application September 11, 1946, Serial No. 696,223
In Great Britain September 11, 1945

9 Claims. (Cl. 123—119)

1

This invention relates to fuel supply systems for internal combustion engines and has for its object to provide means for introducing a liquid anti-detonant into the fuel being delivered to the engine.

It is known that under certain conditions associated primarily with engine speed and boost it is desirable for various reasons to supply an anti-detonant, for example water or a mixture of water and methanol, but it is also desirable to ensure that this anti-detonant is not used except under suitable conditions.

The present improvement is primarily intended for use with a known construction of apparatus in which fuel is delivered under pressure into the induction system.

According to this invention there is combined with apparatus for delivering fuel under pressure into the engine induction passage, a pump which can deliver a liquid anti-detonant to a point at or adjacent to this fuel intake, a regulator for the pressure at which this anti-detonant is delivered, and a metering device for the anti-detonant which is controlled by boost pressure and associated with supercharger speed. The pump which delivers the anti-detonant is electrically driven and the current flowing thereto is controlled on the one hand by an override lever whose position ensures that the pump is cut in only when the engine speed is above a determined figure, and on the other hand by boost pressure above a determined value. The pressure at which the anti-detonant is delivered when the pump is operative controls the setting of a stop which permits movement of a lever by which boost can be selected in excess of a determined pressure, but when the pump delivering the anti-detonant is not operative this stop will automatically prevent this extra movement of the lever and boost selection. The pressure of the anti-detonant when it is supplied by the pump is also operative to bring about a reduction in the richness of the main fuel supply. The means by which the richness of the main fuel supply is thus reduced is associated with the positioning of the above-mentioned stop controlling boost selection.

The accompanying drawing illustrates diagrammatically the improved apparatus in which the invention is embodied.

The apparatus as a whole may be said to comprise the following principal parts which are suitably assembled in combination:

1. A known apparatus for introducing fuel into the engine induction passage through the nose of an impeller situated and rotated in the induction passage.

2

2. A tank containing the liquid anti-detonant and associated with it a pump which delivers this liquid under pressure, but is operative only when a determined boost pressure and engine speed are reached.

3. A regulator which determines the flow of the anti-detonant and the pressure at which it is delivered to mingle with the fuel as injected into the engine induction passage.

4. A metering device which is controlled by boost pressure and determines the amount of anti-detonant delivered this metering being associated with supercharger speed.

5. Means associated with the above mentioned regulator which control a device operative to determine the boost pressure which may be selected.

6. An apparatus associated with the boost selection lever by which the richness of the fuel is automatically reduced when the anti-detonant is supplied.

There is no occasion to describe here in detail the fuel injection apparatus which as mentioned above is substantially in accordance with the description in the specification of British Patent No. 563,643. In that apparatus there is behind the nozzle A, through which the fuel is delivered under pressure into the intake B of the impeller B¹ of the variable speed supercharger of the aircraft motor B², an annular chamber C surrounding the fuel delivery pipe A¹. The anti-detonant is delivered through a pipe C¹ into this chamber C under a pressure which is not less than the pressure of the fuel as delivered to the nozzle A.

As the apparatus is primarily for use with an internal combustion engine in an aircraft the tank D containing the liquid anti-detonant is preferably of a type known as "negative G proof" being adapted to function irrespective of the attitude

of the aircraft. A pump E conveniently electrically driven by a motor D¹, draws the liquid from the tank and delivers it under a pressure, which for example may be of the order of 22 lbs. per square inch, through the pipe E¹. A relief

valve F will lift if the determined delivery pressure is exceeded and then establishes communication through the pipe E² with the tank D or otherwise on the suction side of the pump E. This relief valve F is carried by a diaphragm F¹ on which acts a spring F² and the chamber F³ behind the diaphragm is in communication through piping G with a chamber G¹ around the fuel delivery nozzle, this chamber being in communication as by one or more passageways G² with the intake B. Thus the pressure loading the relief valve F is that of the spring F² and the air

pressure at the intake B. The liquid is first delivered by the pump E through the pipe E¹ into a separator E³ from which the air separated out passes back through a constriction E⁴ and pipe E⁵ to the tank D. The arrangement is such that when the pump is operating the anti-detonant will be delivered at a pressure of approximately 20 lbs. to the square inch above the pressure at the fuel and air intake B.

The pump E, the motor D¹ of which is conveniently driven by current from a battery E⁶, will only deliver anti-detonant liquid when an override lever H has been moved into a determined position corresponding to the selection of an engine speed at or above a predetermined figure. Lever H is moved by the pilot when he wishes the engine to run at such higher speed and the lever is connected to the engine governor H² by a linkage H³ so that the governor is given a new setting to permit the engine to run at the higher speed when lever H is so moved. The pump is also permitted to be operative only when the engine boost pressure is at or above a predetermined figure. Movement of the override lever H will close contacts H¹ in the pump motor circuit, while a capsule J in a chamber J¹ is subjected to boost pressure through a pipe J² and this capsule can close contacts J³ in the pump motor circuit. The abutment J⁴ of the capsule is adjustable so that the capsule can be set for the minimum boost pressure at which the contacts J³ should be closed and the pump permitted to be operative.

The anti-detonant delivered by the pump E flows from the separator E³ through piping E⁷ to a pressure regulator in a casing K. The regulator in the casing comprises a diaphragm K¹ which carries a valve K² adapted to seat in a port K³ in a partition K⁴, while at the side of this partition opposite to the diaphragm K¹ is a second diaphragm K⁵ which is connected to a double-acting valve of which one part K⁶ is adapted to shut off the supply of oil under pressure which actuates certain parts of the apparatus, this oil supply coming through the pipe L from an engine-driven pump (not shown). The other part K⁷ of this valve controls the flow-off of this pressure oil through the pipe L¹. The diaphragm K¹ is loaded by a spring K⁸ and by the pressure of the anti-detonant after metering and as it flows to the fuel nozzle A, this liquid coming through the pipe E⁸ into the chamber K⁹ behind the diaphragm K¹. The diaphragm K⁵ is loaded by a spring K¹⁰ and the chamber K¹¹ behind the diaphragm is in communication through the pipe G³ with the pipe G in which is air at the pressure existant at the intake B. The pipe E⁷ through which the anti-detonant is delivered by the pump leads into the chamber K¹² at one side of the partition K⁴ and the liquid which is allowed to flow according to the setting of the valve K² through the port K³ into the chamber K¹³ is led by the pipe E⁹ to the metering device.

The metering device comprises a casing M which is divided into three compartments M¹, M² and M³ by two partitions M⁴ and M⁵. In each of these partitions is a port and the two valves M⁶ and M⁷ controlling these ports are mounted on a spindle M⁸ which extends for example downwards from a capsule M⁹ disposed in a chamber M¹⁰ which is subjected to boost pressure through a pipe J⁵. The abutment M¹¹ at the end of the capsule M⁹ opposite to the spindle M⁸ is adjustable. The anti-detonant from the

regulator K enters the central compartment M² of the metering device through the pipe E⁹, and the main flow of metered liquid takes place through the port in the upper partition M⁴ controlled by the valve M⁶ and this flow, which is metered in accordance with boost pressure, takes place through a pipe E¹⁰ which joins the pipe E⁹ and in the manner to be described hereunder communicates with the pipe C¹ and the annular chamber C around the fuel delivery pipe A¹.

The flow of liquid through the port in the lower partition M⁵ which is controlled by the valve M⁷ is additional to the flow through the port controlled by the valve M⁶ and it takes place through a pipe E¹¹ leading from the lower compartment M³ and like the pipe E¹⁰ joining the pipe E⁹. In the pipe E¹¹ is a cock N connected through the lever N¹ and the links and levers N², N³, N⁴, N⁵ and N⁶ to the supercharger gear change lever O. The cock N will be shut when the lever O is set in the position O^a for moderate speed, but will be fully open when the lever O is set in the position O^b for full supercharger speed. The supercharger gear change lever O is manually operated and is connected up in a known manner as follows. An extension N⁷ of the linkage N⁶ connects with the operating lever of a three-way cock O^c; one way O^d of this cock is connected to the pressure oil supply through a pipe L⁴, and the other ways O^e and O^f communicate respectively with the moderate speed clutch B⁵ and the full speed clutch B⁶ in the supercharger change speed mechanism B³. When the lever O is in the position O^a pressure oil flows through the ways O^d and O^e and causes the moderate speed clutch B⁵ to engage. When the lever O is in the position O^b pressure oil flows through the ways O^d and O^f and causes the full speed clutch B⁶ to engage. The setting of the regulator K ensures a small pressure drop across the metering orifices in the partitions M⁴, M⁵ and this pressure difference can be accurately set by adjustment of the spring K⁸ in the regulator K which loads the diaphragm K¹ with the valve K². Thus as mentioned the flow of anti-detonant in accordance with moderate supercharger speed is metered by the valve M⁶ in accordance with boost pressure while the flow in accordance with full supercharger speed will be an additional amount metered by the valve M⁷, the amount being determined by the setting of the cock N in correspondence with the position of the lever O. Hence the flow through the two ports controlled by the valves M⁶ and M⁷ takes place when under full supercharger speed conditions.

The anti-detonant from the metering device M flows by way of the pipe E⁸ into a casing P which is divided by a diaphragm P¹ into chambers P² and P³. The diaphragm P¹ functions as a valve in conjunction with an annular projection P⁴ in the chamber P² and thus controls the flow of anti-detonant from the part of the chamber P² within the annular projection P⁴ into the part of the chamber P² which is outside the annular projection P⁴. From the latter part of the chamber P² the anti-detonant passes by way of the pipe C¹ to the chamber C around the fuel delivery pipe A¹. The diaphragm P¹ is loaded first by a spring P⁵ and by the action of the operating pressure liquid in the system as permitted to flow through the pipe L² and act in a cylinder on a plunger P⁶ which projects from what may be called the back of the diaphragm P¹. Pressure liquid can drain from the chamber P³ at the back of the diaphragm to the intake B through

piping Q of which a branch Q¹ also runs to the gland through which passes the spindle M⁸ which carries the valves of the metering device. The valve contained in the casing P constitutes in effect a safety device to prevent fuel from flowing back from the nozzle A into the anti-detonant system should the supply of anti-detonant fail for any reason.

The sequence of events in the apparatus as so far described is as follows. The pump E builds up the pressure of the anti-detonant liquid in the central chamber K¹² in the regulator K and by acting on the diaphragm K⁵ moves the valve K⁶ downwards, stopping the flow of pressure oil or other liquid entering by the piping L. Simultaneously as the valve K⁷ moves off its seating the drain L¹ for the pressure liquid is opened, thereby relieving the pressure in the piping system L². The liquid anti-detonant under pressure flowing through the piping E⁹, the metering device M and the piping E¹⁰, E⁸ into the chamber P², acts on the diaphragm valve P¹ against the spring P⁵ and this valve is lifted and allows the anti-detonant to flow through the piping C¹ and the chamber C to the nozzle A. The diaphragm valve P¹ in effect acts as a static head valve and when it cuts off the supply of anti-detonant, as when the valve P¹ is seated by the pressure of the liquid in the piping L², it serves to prevent the back flow of fuel from the nozzle A into the chamber C and piping C¹ and so into the anti-detonant system. Oil leakage from the piping L² past the plunger P⁶ into the chamber P³ drains away by the piping Q to the intake B and this piping serves to balance the pressure on the diaphragm P¹ by placing the chamber P³ in communication with the datum pressure at the intake B.

When the supply of anti-detonant under pressure operating in the central chamber K¹² of the regulator K cuts off the supply of pressure oil through the pipe L, the relief by opening the drain L¹ in the pressure oil system reduces in a cylinder R the pressure of this oil supply on one side of the piston R¹, since the one end of this cylinder is in communication through the piping L² with the pressure oil system. The spring R² acting on the piston R¹ then moves this piston and a two-armed lever R³, R⁴ to the arm R⁵ of which the piston R¹ is connected. On the same pivot R⁵ about which the lever R³, R⁴ can turn is a lever R⁶ connected with a pilot operated boost selection lever not shown. The boost selection lever actuates a throttle valve in the supercharger intake and thus controls the boost pressure. This arrangement is well known in itself and is therefore not shown in the drawing. The lever R⁶ has a tail R⁷ which can come into contact with a stop R⁸ on the arm R³ of the lever which is connected to the piston R¹. When the pressure in the piping L² is relieved and the piston R¹ able to move into the position in which it is indicated in the drawing, it is possible for the boost lever R⁶ to be moved from the position indicated at R^a, which for example may represent fifteen pounds per square inch boost pressure, into the position R^b when the boost pressure will be increased to, say, seventeen pounds per square inch. When however the pressure liquid in the piping L² is operative, that is to say when for any reason the supply of anti-detonant liquid under pressure fails or is cut off and the valve K⁶ is lifted, the piston R¹ will be moved to the left, as seen in the drawing, carrying with it the lever R³, R⁴. The stop R⁸ will then

prevent the lever R⁶ from being moved from the position R^a and a decrease in the boost pressure brought about. This arrangement prevents the selection of boost pressure above a determined figure unless the pressure of the anti-detonant as delivered by the pump has been built up sufficiently to enable this liquid to be metered and delivered to the fuel nozzle. This part of the apparatus serves also as a safety device since if the pressure in the delivery pipe from the pump E fails, for example as a result of interrupting the current flowing to the pump, the stop R⁸ will obstruct the movement of the lever R⁶ and boost selection above the amount represented by the lever R⁶ when in the position R^a will be prevented.

The arm R⁴ of the lever acted on by the piston R¹ is connected by a link U² to a lever U¹ controlling a cock U in the fuel derichment mechanism described hereunder. The supercharger gear change lever O is similarly connected by a link V⁶ to a lever V¹ controlling another cock V in this derichment mechanism.

This fuel derichment is obtained by reducing the pressure drop across the main fuel metering device and is effected by apparatus which comprises a known construction and arrangement of parts of which the chief features are as follows:

A casing S of suitable shape is divided by a diaphragm S¹ into two chambers S², S³ and in the chamber S² is a valve S⁴ connected to the diaphragm and controlling the flow through that chamber of fuel which is led thence by the pipe A¹ to the injector nozzle A. The fuel enters the chamber S² by a pipe A² leading from a metering device to which the fuel is delivered by a pump (not shown) through the main supply pipe A³. The metering device, of known construction, comprises a sleeve T in which is a port T¹, the sleeve being movable by means not shown, in a casing T² in the wall of which is a port T³ leading to the pipe A². A branch A⁴ from the main fuel supply pipe A³ leads to a subsidiary circuit A⁵ in which is a centrifugal impeller A⁶ and this circuit runs from and returns to the chamber S³ at one side of the diaphragm S¹. In this circuit is arranged the means by which the fuel derichment is effected. In the piping A⁵ through which the fuel is caused to flow by the impeller A⁶ to the chamber S³ is a fixed constriction A⁷ and the variable constriction or cock U which through the lever U¹ and the connecting linkage U² is actuated by the lever R⁴ by the positioning of which boost selection is controlled. The opening or closing of this cock U varies the pressure in the chamber S³ at one side of the diaphragm S¹ movement of which controls the actual flow of fuel to the nozzle A. Since the cock U is actuated through the lever R⁴ which is moved or set in accordance with the pressure at which the anti-detonant is supplied, that is the pressure in the chamber K¹² in the regulator K, derichment of the fuel will occur only when the liquid anti-detonant is flowing at sufficient pressure to ensure the operation of the metering unit M. The pipe A⁸ in the supplementary circuit leading from the chamber S³ to the eye of the impeller A⁶ has two branches A⁹ and A¹⁰. In the branch A⁹ is the cock V actuated by the lever V¹ which is connected by the linkage V⁶ to the lever O controlling the supercharger change speed gear, and in this branch there is also an orifice V² the area of which can be adjusted by a valve V³. Opening of the cock V affects the fuel flow through the pipe A⁸ to the impeller A⁶ and

consequently the pressure in the diaphragm chamber S^3 when the lever O is in the position O^a for moderate gear ratio in the supercharger drive. In the other branch A^{10} of the piping is an orifice V^4 the area of which can be adjusted by a valve V^5 in the same way as the orifice V^2 is variable by the valve V^3 . Flow through the orifice V^4 and branch A^{10} is constant and takes place through this branch alone when the lever O is in the position O^b and the supercharger gear is set for full drive ratio, the cock V being then shut. Thus while fuel flow can take place through both the branches A^9 and A^{10} to the impeller A^6 when the supercharger gear is set to moderate drive ratio, on the other hand when the gear is set for full speed the flow through the one branch A^9 will be stopped reducing the amount of fuel which the impeller can draw from the chamber S^3 with the result that there will be a pressure rise in that chamber and consequently movement of the diaphragm S^1 which will partially close the valve S^4 controlling the fuel delivery to the nozzle A and thus effect de-richment of the fuel supply.

The engine conditions obtaining when anti-detonant is supplied with the fuel necessitate an advance in the ignition timing of the order of 6° and this is effected automatically by the following means. In a casing W is a diaphragm W^1 dividing the casing into two chambers W^2 and W^3 and in the chamber W^2 is a spring acting on that side of the diaphragm. On its other side the diaphragm is connected to a piston valve W^4 movable by the diaphragm in a cylinder W^5 and controlling ports W^6 and W^7 in the wall thereof. A cylinder X which is coaxial with the cylinder W^5 is in effect an enlargement at the end of the cylinder W^5 and in this cylinder X is a piston X^1 acted on by a spring X^2 . The end of the cylinder X is in communication with the pressure oil piping L^2 so that when pressure exists in this piping it can act on and move the piston X against the spring X^2 and into contact with the end of the valve W^4 moving it against the spring acting on the diaphragm W^1 . Piping J^6 in which is boost pressure communicates with the port W^6 in the cylinder W^5 and with the chamber W^3 at one side of the diaphragm W^1 . Piping Y leading from the port W^7 in the cylinder W^5 and from the chamber W^2 runs to an ignition control unit Y^1 which is adapted to be actuated by boost pressure and operates automatically to alter the ignition timing of a magneto or coil Y^2 . Piping L^3 leads from a port W^8 in the cylinder W^5 and from a port X^3 in the cylinder X and serves to drain away oil from these cylinders. This apparatus operates in the following manner. When anti-detonant is being delivered and the consequent pressure in the chamber K^{12} in the regulator K closes the valve K^6 and cuts off the supply of pressure oil from the pipe L , there is a pressure drop in the cylinder X behind the piston X^1 which is then moved by the spring X^2 away from the end of the valve W^4 which can then assume the position in which it is shown in the drawing wherein it has closed the port W^6 . This shuts off the boost pressure from the piping Y with the effect in the ignition control unit Y^1 of automatically advancing the ignition timing to the required extent. On the other hand when the pump delivery of the anti-detonant ceases and the pressure in the chamber K^{12} in the regulator K drops, the valve K^6 is moved and admits pressure oil again to the system and flowing through the piping L^2 enters

the cylinder X and moves the piston X^1 into contact with the end of the valve W^4 which is then moved so as to uncover the port W^6 and allow the passage of boost pressure into the piping Y with the effect in the ignition control unit that the ignition timing is restored to normal. At starting the port W^8 in the cylinder W^5 is uncovered thus ensuring a reduction in the pressure in the piping Y in accordance with normal starting requirements.

What I claim as my invention and desire to secure by Letters Patent is:

1. A system for supplying fuel and a liquid anti-detonant to an internal combustion engine provided with a supercharger in its induction passage, variable speed driving means for driving said supercharger from the engine and a control for setting the speed ratio of said driving means, said system comprising means for delivering a metered quantity of fuel under pressure through a nozzle into the engine induction passage, a pump which when operative delivers anti-detonant to said nozzle so that it will mingle with the fuel issuing therefrom, a pressure regulator for regulating the pressure of the anti-detonant delivered to said nozzle, a main metering device through which anti-detonant passes on its way to the nozzle and adapted to meter the quantity of anti-detonant passing therethrough in dependence upon the engine boost pressure, an additional anti-detonant metering device for admitting an additional supply of anti-detonant to said nozzle, and means for rendering said additional metering device operative only when the supercharger driving means is set for driving the supercharger at the highest speed ratio.
2. A fuel and anti-detonant supply system for an internal combustion engine comprising the parts as set out in claim 1 and in which the said pump which delivers the anti-detonant is electrically driven and the supply of current thereto is controlled on the one hand by an override lever whose position ensures that the pump is operative only when the speed of the engine is set between determined limits, and on the other hand by means controlled by engine boost pressure.
3. A fuel and anti-detonant supply system for an internal combustion engine comprising the parts as set out in claim 1 and in which there is a lever by movement of which boost in excess of a determined pressure can be selected, a stop the positioning of which controls the setting of the said lever and thereby the selection of boost pressure, and means whereby when the said pump is operative and delivering anti-detonant the pressure at which the anti-detonant is delivered will control the setting of the said stop so that when the pump is operative the said lever can be moved to select boost in excess of a determined pressure but when the pump is not operative the stop will prevent that boost selecting movement of the said lever.
4. A fuel and anti-detonant supply system for an internal combustion engine comprising the parts as set out in claim 1 and including a pipe system to which liquid under pressure is supplied, a valve serving to shut off the delivery of anti-detonant to the said fuel injection nozzle, means for actuating this valve by the said pressure liquid, means for selecting boost pressure including means whereby this selection can be affected by the action of the said pressure liquid, means actuated by this pressure liquid for varying the ig-

nition timing in the engine, and means whereby the supply of pressure liquid to the said pipe system is controlled by the pressure of the anti-detonant in the said regulator.

5. A fuel and anti-detonant supply system for an internal combustion engine comprising the parts as set out in claim 1 and including means whereby a reduction can be effected in the richness of the fuel supply to the engine, and means whereby the pressure of the anti-detonant as and when delivered by the said pump can bring about the said reduction in the fuel supply.

6. A system for supplying fuel and a liquid anti-detonant to an internal combustion engine provided with a supercharger in its induction passage, variable speed driving means for driving said supercharger from the engine and a control for setting the speed ratio of said driving means, said system comprising means for delivering a metered quantity of fuel under pressure through a nozzle into the engine induction passage, a pump which when operative delivers anti-detonant to said nozzle so that it will mingle with the fuel issuing therefrom, a pressure regulator for regulating the pressure of the anti-detonant delivered to said nozzle, a main metering device through which anti-detonant passes on its way to the nozzle, an additional metering device in parallel with said main metering device these metering devices being adapted to meter the quantity of anti-detonant passing therethrough in dependence upon the engine boost pressure, means for shutting off the flow of anti-detonant through said additional metering device, and an operative connection between said shut-off means and said control for the supercharger driving means whereby anti-detonant is permitted to flow to the nozzle through said additional metering device only when the supercharger driving means is set for driving the supercharger at the highest speed ratio.

7. A system for supplying fuel and a liquid anti-detonant to an internal combustion engine provided with a supercharger in its induction passage, variable speed driving means for driving said supercharger from the engine and a control for setting the speed ratio of said driving means, said system comprising means for delivering a metered quantity of fuel under pressure through a nozzle into the engine induction passage, means for reducing the supply of fuel through said nozzle, a pump which when operative delivers anti-detonant to said nozzle so that it will mingle with the fuel issuing therefrom, means whereby said pump is permitted to be operative only when an override lever is in a position in which the engine speed is set between determined limits and there is a determined boost pressure, a control by movement of which boost in excess of a determined pressure can be selected, a stop the positioning of which limits the setting of said boost selecting control, means whereby when said pump is operative and delivering anti-detonant the pressure at which the anti-detonant is delivered will control the setting of said stop so that when said pump is operative said control can be moved to select boost in excess of the determined pressure but when said pump is not operative the stop will prevent that boost selecting movement of said control, means whereby the setting of said stop to permit selection of a boost pressure in excess of said determined pressure actuates said means for reducing the fuel supply, a pressure regulator for regulating the pressure of the anti-detonant delivered to said nozzle, a main metering device

through which anti-detonant passes on its way to the nozzle and adapted to meter the quantity of anti-detonant passing therethrough in dependence upon the engine boost pressure, an additional anti-detonant metering device for admitting an additional supply of anti-detonant to said nozzle, and means for rendering said additional metering device operative only when the supercharger driving means is set for driving the supercharger at the highest speed ratio.

8. A system for supplying fuel and a liquid anti-detonant to an internal combustion engine provided with a supercharger in its induction passage, variable speed driving means for driving said supercharger from the engine and a control for setting the speed ratio of said driving means, said system comprising means for delivering a metered quantity of fuel under pressure through a nozzle into the engine induction passage, a pump which when operative delivers anti-detonant to said nozzle so that it will mingle with the fuel issuing therefrom, a pressure regulator for regulating the pressure of the anti-detonant delivered to said nozzle, said pressure regulator comprising a casing, a ported partition dividing said casing into first and second chambers to the first of which anti-detonant is delivered by said pump, a diaphragm constituting a wall of said first chamber, a spring acting on said diaphragm, a valve controlling the supply of a liquid under pressure to a pipe system, a connection between said diaphragm and said valve, a second diaphragm in said pressure regulator constituting a wall of said second chamber, a spring acting on said diaphragm, a valve connected to said diaphragm and controlling the size of the port in said partition and hence the pressure drop of the anti-detonant in passing from the first chamber to the second chamber, a main metering device to which anti-detonant passes from said second chamber on its way to the nozzle and adapted to meter the quantity of anti-detonant passing therethrough in dependence upon the engine boost pressure, an additional anti-detonant metering device for admitting an additional supply of anti-detonant to said nozzle, means for rendering said additional metering device operative only when the supercharger driving means is set for driving the supercharger at the highest speed ratio, and a valve serving to shut-off the delivery of the anti-detonant to said nozzle actuated in response to the liquid pressure in the said pipe system, whereby said valve is closed when the pressure of the anti-detonant delivered to said pressure regulator falls below a predetermined value.

9. A fuel and anti-detonant supply system for an internal combustion engine comprising the parts as set out in claim 8 in which said metering devices include a casing divided by two partitions into three chambers with a port in each partition, a capsule subjected to boost pressure and carrying a spindle on which are two valves respectively adapted to engage the ports in the said two partitions, piping through which the anti-detonant from the said regulator enters the first and central one of the three said chambers in the metering device with piping leading from the second of these chambers to the said valve serving to shut off the delivery of anti-detonant to the said nozzle, piping leading similarly from the third of the said chambers, a valve in said latter piping from the third chamber with means for actuating this valve in

11

accordance with the speed setting of the engine supercharger.
